UNITED STATES PATENT OFFICE.

ALBERT WILSON, OF CHICAGO, ILLINOIS.

TYPE-FRAME LIFTER.

Application filed June 14, 1926. Serial No. 115,719.

My invention relates to a type frame lifter, and the same has for its general object the provision of a tool or implement whereby quickly to raise up a binding frame or device 5 on type composition.

One of the main objects of my invention is the provision of a lifter of this character, which will embody certain desired features of simplicity, efficiency and convenience, and 10 which will be economical in manufacture and durable in use.

Another object is the provision of a tool or implement for raising the frame on the bound or tied type composition to an elevation 15 that will permit of the ready application of the usual "furniture" pieces employed in separating one page or section of the type composition from another; and further to provide a tool or implement so constructed 20 and arranged that the type binding frame will be raised without disturbing or disarranging the type composition itself.

In its broad aspect, my invention involves means for bearing upon the type composition 25 and rockable means arranged on the bearing means for engaging the binding frame and drawing it up evenly all around the type composition. The invention involves means by which readily to position the 30 lifter upon the binding frame holding the type composition; and it further involves a construction of means by which the lifter, when raised to the desired height, will be automatically disengaged from the binding frame.

Other objects will appear hereinafter.

The invention consists in the combinations and arrangements of parts hereinafter described and claimed.

The invention will be best understood by reference to the accompanying drawings, forming a part of this specification, and in which,

Fig. 1 represents a side elevational view of 45 my lifter showing it applied to a type binding frame and with the parts in the position they occupy when the operating handle is in elevated position;

Fig. 2 represents a side elevational view of 50 the lifter showing the parts in the position they occupy when the operating handle is depressed and the binding frame elevated for the application of the "furniture", the binding frame here being shown in section;

Fig. 3 represents a top plan view of the 55 lifter, this view being taken with the parts

in the position they occupy in Fig. 2, looking in the direction of the arrows associated with the line 3-3;

Fig. 4 is a cross section taken on the line 60 4-4 of Fig. 2; and,

Fig. 5 is a detail section taken on the line 5-5 of Fig. 1.

In the drawings, wherein for the purpose of illustration I show a preferred embodiment of my invention, the numeral 6 designates a base piece or plate adapted for placement upon the type composition 7 held by a binding frame 8, here shown as composed of opposed side walls 9 and 10 and opposed 70 end walls 11 and 12, said side and end walls being connected at their corners by outside hinges 13. Rising centrally from the base piece 6 is a post 14 in which is cut a longitudinally extending slot 15. Also rising from 75 the base piece at suitable points on opposite sides of the center post are transversely extending U-shaped brackets 16, each carrying an axis rod 17, there being one of such brackets suitably positioned between the center post and what may be termed the rear 80 end 18 of the base piece, and another of such brackets located between the center post and what may be termed the front end 19 of the base piece.

Mounted for rocking up and down movement upon each of the axis rods 17 are a pair of forks 20 comprising branches of a rocking lever 21. The inner ends of the two rocking levers are movably connected to the 90 center post 14; and to this end each of the rocking levers is provided with an elongated slot 22 at its inner end and a suitable pin member 23 is taken through the center post slot 15 and also through the rocking lever 95 slots 22.

The means for moving the rocking levers up and down comprises a handle 24 in which are incorporated two similar body plates 25 held by pins 26 and provided near the front 100 end of the handle with depending shanks 27 formed with forwardly offset portions 28 adapted to straddle the center post and rocking lever ends, the said portions 28 being pivotally secured upon the pin 23. Preferably and as shown, the handle is also supported at its rear end by means of a down curved shank 29 which is pivotally mounted at its upper end on the rear pin 26 and to the lower end of which are secured oppositely 110 directed branches 30 having lugs 31 pivoted upon the axis rod 17 on the bracket at the

2
 rear end of the base piece. Thus mounted, the handle is movable from the elevated position shown in Fig. 1 to the depressed position shown in Fig. 2. In order to releasably hold the handle in elevated position against depression, a latch member 32 is pivoted at 33 to the front end of the handle and is formed with a thumb piece 34 projecting over the same, the lower end of the latch member being bent as at 35 to engage in a notch 36 on the top of the center post. A spring member 37 conveniently applied to one of the pins 26 bears upon the thumb piece 34 so as to automatically snap the bent end 35 into its notch when the handle is moved into elevated position, it being observed that the pin 23 serves as a stop to determine the terminal of elevation for the handle. By making pressure on the thumb piece 34, the latch will be disengaged from the notched top end of the post, whereupon the handle may be depressed to the position shown in Fig. 2, thereby rocking the levers 21 so as to elevate the ends of the branches 20 which it will be observed extend beyond the ends of the base piece.

For lifting up the binding frame 8 when the handle is depressed, a lifting shoe 37' is pivoted at 38 upon the outer end of each of the branches 20, said shoes being of hollow construction so that the outer ends of the branches extend into the bodies of the shoes as best shown in Figs. 1 and 2. The top ends of the shoes are given a cam-like form as at 39 to cooperate with the outer ends of strip springs 40 secured as by screws 41 upon the branches. Pull springs 42 connect the top ends of the shoes with upturned lugs 43 formed on the strip springs 40. The pull springs 42 tend to draw the lifting shoes into substantially vertical position as shown in Fig. 1 with the cam-like portions 39 engaged on the ends of the strip springs 40. Each of the shoes 37 is formed at its lower end with a hook 44 adapted to engage a hook-shaped lug 44' arranged for the purpose on the binding frame 8. The exact height to which the binding frame may be raised by the depression of the handle is determined by an adjusting screw 45 which is threaded through a laterally projected lug 46 formed on one of the shank portions 28 as clearly shown in Fig. 4. This adjusting screw upon the depression of the handle engages the base piece and thereby acts as a stop. Coiled about the center post 14 is a spring 47 arranged to be compressed by the rocking levers when the handle is depressed; the purpose of this spring being to serve as resilient means for automatically reversing the rocking levers immediately upon the handle being released when moved to its lowest point where the adjusting screw engages the base piece.

65 According to a feature of my present in-

vention, I provide means for positioning the lifter upon the binding frame to be lifted. This means comprises the provision of brackets 48 which are secured as by screws 49 to the branches 20 in proximity to the lifting shoes 37. The brackets 48 are downwardly offset as shown and terminate in feet 50 which are preferably upwardly deformed as at 51 in order to seat upon the top ends of the hinges 13 of the binding frame.

It may be mentioned here that my lifter is designed especially for use in connection with type frame binders of the type disclosed in my applications for Letters Patent of the United States, filed on December 19, 1925, Serial No. 76,354, and filed on March 4, 1926, Serial No. 92,278; but it is to be understood that my lifter may be employed for raising other kinds of type frames and also may be employed in all places and capacities involving lifting operations and for which it may be adapted. In the use of my lifter, the handle is first moved into elevated position as shown in Fig. 1 so as to incline the outer ends of the branches downwardly with the hooks of the lifting shoes projecting below the base piece. The lifter is then applied to the frame by first seating the feet 50 at the rear end of the device upon the hinges of the binding frame 8 and in effecting this seating operation the hooks of the lifting shoes are slipped into engagement with the hooks 44' on the frame end 12. The base piece is then moved down to rest upon the type composition held in the binding frame and finally the feet 50 are seated upon the hinges adjacent the front end of the base piece, the hooks on the lifting shoes adjacent the front end during the seating operation slipping into engagement with the hooks 44' on the front end 11 of the binding frame. Thereupon the latch 32 is tripped and the handle depressed until the adjusting screw 45 contacts with the base piece, and thereupon the handle is released so that the spring 47, which was compressed by the descent of the rocking levers, will react to reverse the movement of the levers so as to move the outer ends of the branches with the lifting shoes in downward direction. During the depression of the handle, the lifting frame, owing to the interengagement of the hooks on the lifting shoes with the hooks on the lifting frame, is elevated evenly all around the type composition held thereby, and as the movement of the rocking levers is reversed by the expansion of spring 47, which action lowers the lifting shoes sufficiently to enable their hooks to be disengaged from the lifting frame hooks, the pull springs 42 operate to draw the shoes into position to clear their hooks from the hooks of the lifting frame. Through the adjusting screw 45, the lifter may be regulated so as to raise the lifting

frame high enough to permit the usual "furniture" pieces 52 to be placed against the sides of the lifting frame as clearly illustrated in Figs. 2, 3 and 4. The lifting frame 5 then may be withdrawn entirely from the type composition when convenient.

While I have illustrated and described the preferred form of construction for carrying my invention into effect, this is capable 10 of variation and modification without departing from the spirit of the invention. I, therefore, do not wish to be limited to the precise details of construction set forth, but desire to avail myself of such variations and 15 modifications as come within the scope of the appended claims.

Having described my invention what I claim as new and desire to secure by Letters Patent is:

20 1. A device for lifting a type frame from type composition held therein including a supporting means, a lifting means on the supporting means, and a handle for operating the lifting means.

25 2. A type frame lifter comprising a supporting piece; rocking levers mounted upon the supporting piece and carrying lifting shoes; and means associated with said levers by which to operate the same, substantially 30 as described.

35 3. A type frame lifter comprising a supporting piece; means associated with the supporting piece for positioning it upon the type frame to be lifted; rocking levers mounted upon the supporting piece and carrying lifting shoes for raising the type frame; and means associated with said levers by which to operate the same, substantially 40 as described.

45 4. A type frame lifter comprising a supporting piece adapted to be placed upon type composition; levers mounted upon the supporting piece to have up and down movement; devices arranged on said levers to position the lifter upon the type frame; lifting shoes on the levers for engaging and raising the type frame; and means by which to impart motion to said levers, substantially 50 as described.

55 5. A type frame lifter comprising a supporting piece adapted to be placed upon type composition; a post rising from the supporting piece; levers mounted for up and down rocking movement on said supporting piece and having their inner ends movably associated with said post; a handle connected to the inner ends of said levers by which to impart movement thereto; and 60 lifting shoes pivotally arranged on the outer ends of said levers for engaging and raising the type frame, substantially as described.

65 6. A type frame lifter comprising supporting means; levers mounted upon the supporting means for rocking movement

and having branched outer ends; means for rocking said levers; and lifting shoes adapted to engage and raise the type frame pivotally mounted upon said branches, substantially as described.

70

7. A type frame lifter comprising a supporting piece; rocking levers mounted upon the supporting piece; lifting shoes with hooks pivotally arranged on the rocking levers and adapted to engage and raise the 75 type frame; and spring means associated with said levers and lifting shoes for controlling the lifting shoes, substantially as described.

8. A type frame lifter comprising a supporting piece; rocking levers mounted upon the supporting piece; lifting shoes with hooks pivotally mounted on the rocking levers and provided with cam-like portions; spring means on the rocking levers arranged 80 to cooperate with said cam-like portions; and spring means arranged to urge the shoes in a direction to engage said cam-like portions with said first named spring means, 85 substantially as described.

90 9. A type frame lifter comprising a supporting piece for placement on the type composition; rocking levers mounted upon said supporting piece for up and down movement; lifting shoes with hooks pivoted 95 on the outer ends of said levers for engaging and raising the type frame relatively upon the type composition; and means for limiting the movement of said levers to determine the height to which the type frame 100 shall be raised, substantially as described.

105 10. A type frame lifter comprising a supporting piece for placement on the type composition; rocking levers mounted upon said supporting piece for up and down movement; lifting shoes with hooks pivoted on the outer ends of said levers for engaging and raising the type frame relatively upon the type composition; means for limiting the movement of said levers at a set point to determine the height to which the type frame shall be raised; and spring means arranged to resist the movement of said levers toward said set point, substantially 110 as described.

115 11. A type frame lifter comprising a supporting piece for placement on the type composition and provided with a post; rocking levers mounted upon said supporting piece 120 for up and down movement; lifting shoes pivoted on the outer ends of said levers for raising the type frame relatively upon the type composition; a handle associated with said levers for moving the same and provided with means for locking said levers at up position to said post; and means arranged on said handle to contact the supporting piece and limit the down movement of said levers, substantially as described.

130

12. A type frame lifter comprising a supporting piece for placement on the type composition and provided with a post; rocking levers mounted upon said supporting piece for up and down movement and having their inner ends operatively connected with said post; lifting shoes pivoted on the outer ends of said levers for raising the type frame relatively upon the type composition; a handle for moving said levers and provided with means for locking the same at up position to said post; a stop on the handle to contact the supporting piece and determine the down movement of said levers; and a spring on the post arranged to be compressed under the down movement of said levers so as to force the reverse movement thereof on the release of said handle, substantially as described.
13. In a type frame lifter, the combination with a base piece, of a rocking lever mounted thereon for up and down movement; a lifting shoe on one end of said lever to be raised up from said base piece as the opposite end of said lever moves toward the same; and means for imparting movement to said lever, substantially as described.
14. In a type frame lifter, the combination with a base piece, of a rocking lever mounted thereon for up and down movement; a lifting shoe on one end of said lever to be raised up from said base piece as the opposite end of said lever moves toward the same; a handle for moving said lever; and means for limiting the movement of said handle, substantially as described.
15. In a type frame lifter, the combination with a base piece, of a rocking lever mounted thereon for up and down movement; a lifting shoe on one end of said lever to be raised up from said base piece as the opposite end of said lever moves toward the same; handle means for moving said lever; means for limiting the down movement of said lever to determine the extent to which said lifting shoe shall be raised; and a spring compressible by the down movement of the lever to automatically cause reverse movement thereof on the release of said handle means, substantially as described.
16. A type frame lifter comprising a base piece with a slotted post; a pair of levers mounted upon said base piece for rocking up and down movement and having slotted inner ends; a pin taken through said slotted post and slotted inner ends whereby the levers are operatively mounted to said post;
17. A type frame lifter comprising a base piece with a post; a pair of levers mounted upon said base piece for rocking up and down movement and having their inner ends operatively mounted on said post; a handle for moving said levers; lifting shoes pivotally mounted on the free ends of said levers; and means combined with the handle and cooperating with said post for locking said levers to said post at one position, substantially as described.
18. A type frame lifter comprising a base piece with a post; brackets rising from said base piece at opposite sides of said post; levers pivoted between their ends on said brackets and having their inner ends movably mounted on said post; lifting shoes pivoted on the free ends of said levers; and a handle having pivotal connection upon the inner ends of said levers and upon one of said brackets for swinging movement to rock said levers, substantially as described.
19. A type frame lifter comprising a base piece with a post; brackets rising from said base piece at opposite sides of said post; levers pivoted between their ends on said brackets and having their inner ends movably mounted on said post; lifting shoes pivoted on the free ends of said levers; and means on said levers in proximity to said lifting shoes for positioning the lifter upon the type frame, substantially as described.
20. A type frame lifter comprising a plate; a post rising therefrom; a lever mounted upon said plate for rocking up and down movement and having one end movably associated with said post; means for rocking said lever; a lifting shoe with a hook fitted on the free end of said lever; means associated with the rocking lever and lifting shoe for holding the latter resiliently positioned on its pivot to cause the hook to slip into engagement with an article when the shoe is in down position and to slip out of engagement with the held article when the shoe is in up position; and a spring on the post compressible by the lever to cause the lever to automatically react to carry the shoe toward down position, substantially as described.

In testimony whereof I have signed my name to this specification.

ALBERT WILSON.
